(57) CLAIM

The ornamental design for a large foliage inspired tray liner, as shown and described.

DESCRIPTION

FIG. 1 is a top perspective view of a large foliage inspired tray liner showing my new design; and

FIG. 2 is a front planar view thereof; and,

FIG. 3 is a rear planar view thereof.

The broken lines are for illustrative purposes only and form no part of the claimed design.

1 Claim, 3 Drawing Sheets
